UNITED STATES PATENT OFFICE

JOSEPH HAULIK, OF DURANT CITY, PENNSYLVANIA

FURNACE

Application filed October 15, 1929. Serial No. 399,797.

The present invention relates to furnaces used in the manufacture of glass, and a new arrangement of the principal parts of such a furnace is adopted herein, to accomplish the following purposes.

Due to the removal of the producer gas generators, usually located between the gas and air regenerators, in such furnaces, the ventilation of the casting hall basement, 10 which is located beneath the factory floor, is much improved, and a temperature thereby obtained, which is very desirable for the workmen around this portion of the glass furnace; and secondly due to the same constructive change, the cleaning of the gas and air regenerator chambers, is accomplished with much more ease than with the common type of furnace, due to the ability of the workmen to clean the interior of the said gas 20 and air regenerator chambers from the outer and inner ends of same, all of which will be more fully described as this specification proceeds herein.

Another feature of the present furnace is that due to a proper and certain location of the burner ports at each end of the furnace hearth chamber, the burning gases in said chamber are directed in their flow, over the tops, and not against the top portions of the 25 glass pots which are being heated in the said chamber, thereby extending greatly the life of the glass pots, as will be explained herein.

Also due to a vertical delivery of gas in certain gas delivery passages in the furnace, 30 the inner wall of the said flues, are not "burned out" as quickly as heretofore, as will be fully described.

The "binding" of the glass furnace is made to much greater advantage, due to the ease 35 with which this may be done with the present type of furnace, and bulging of the central portion of the furnace is prevented, due to the shorter length to be encompassed by the longitudinal binding channels. This will be explained below, and it will be seen that this 45 feature also extends the life of the furnace before it becomes necessary to rebuild it.

The gas and air valves used in connection 50 with the present furnace are placed further apart, and from the furnace proper, than is

usual with glass furnaces, to make them more accessible in cleaning and they are also so placed, to avoid the excessive heat which proximity to the furnace chambers has led to hard and uncomfortable manipulation of 55 these parts of the furnace installation.

Another important feature in my invention is the use of "self-cleaning hearth stones" which are part of the furnace hearth, made of heat resistant clay, and in sections, which 60 are shaped and inclined towards small outlet openings in the walls of the furnace at the focal point of the stones, whereby the overflow of glass and débris from the glass pots, collects practically automatically by 65 gravity and is easily collected at the small portholes just named. The use of a number of these "self-cleaning stones," in each furnace hearth chamber, abolishes the use of "scrapers" used heretofore for cleaning the 70 furnace hearth, having long handles substantially fifteen or sixteen feet in length, which were necessary, due to the inability of the workmen to stand the great heat of the furnace hearth chamber, when the doors of same 75 were opened for scraping purposes. The full details of this feature will be disclosed below.

A constructional feature has also been adopted in my invention, in the use of brick supporting arches to support the "checker-work" which are placed over the air and gas regenerator flues, in the regenerator chambers, instead of plain tile, heretofore used for the purpose named. The fire-brick arches last longer due to their greater strength, and 80 hold the checker-work brick in position longer than the plain tile, thereby extending the useful life of the regenerators as is easily understood, and will be further described.

A novel arrangement of ventilating and 85 cooling chambers and flues for cooling the furnace hearth is adopted in the present invention as will be set out, and which is a device of much utility, and in combination with the many other features herein, has produced a furnace of great practical and invention 90 advantage in the art in which the invention is used.

In the drawings forming part of the present specification,

Figure 1 is a foundational horizontal section through the furnace taken on line 1—1 of Figure 8.

Figure 2 is a vertical cross-section through gas and air flues taken on line 2—2 of Figure 1.

Figure 3 is a horizontal section on line 3—3 of Figure 8, showing the ventilation or air cooling flues which lie beneath the furnace hearth, the surface of the latter being removed for clearness of illustration.

Figure 4 is a horizontal section of the furnace taken on line 4—4 of Figure 8, with the rider-arch brick being removed from one-half of the furnace regenerator flues.

Figure 5 is a horizontal section through the furnace on line 5—5 of Figure 8, showing the interior of the furnace hearth chamber, with various sizes of glass pots disposed on the hearth.

Figure 6 is an end view of Figure 5, taken from the right thereof.

Figure 7 is a central transverse section of the furnace installation, showing the stack, and the flues leading thereto, taken on line 7—7 of Figure 4.

Figure 8 is a vertical section of the furnace on line 8—8 of Figure 5.

Figure 9 is a side elevation of the furnace partly in section taken on line 9—9 of Figure 4.

Figure 10 is a perspective view of two of the brick rider arches, and associated parts, used to support the checker-work brick, in the regenerator chambers of the furnace.

In the drawings the numeral 1 indicates a glass furnace, having the following parts. Numeral 13 indicates a furnace hearth chamber, having the usual side walls 78, 79, hearth 40 14, and arched roof 80. The hearth 14 is cooled by the chamber 70, lying immediately beneath it, and having the respective inlet ports and outlet flues 74, 75 for providing a circulation of air through chamber 70, and the lower side of the furnace hearth 14.

Beneath the cooling chamber 70 are located two banks of gas and air regenerators, to wit, 9, 31, 51, and 20, 34, and 35, the first being designated as group 58, and the latter as group 59. The chambers 9 and 20 are usually called the gas regenerators, since at certain periods of operation, the gas flows through them exclusively, while all the other chambers of these two groups are called or named the air regenerators, for a similar reason. These regenerative chambers are provided with rider arches or arched brick 30, 30 etc. which are placed over or span the passages which are beneath them, and on these rider brick are placed a series of openly disposed brick (not shown), which are called the checker-work brick, commonly used for reheating the gases and air at certain periods of operation of the furnace.

Certain flues or passages are located be-

neath the regenerative chambers just described, and beneath the arched passageway 52, and these leading-in, and leading-out passages such as 28, 36, 24, 39, 68, 7, 23, are used to convey gas and air, and the products of their combustion to and from the air-valves 2 and 41, and the stack 25, their method of use being described below.

Leading from the regenerators 9, 31, 51, etc. are certain flues such as 11, 32, 69, and 19, 65, 66 which carry air or gas, or both to the chambers 12 and 18, and thereby to the furnace hearth chamber 13, the operation of these passages also being set out in detail hereinafter.

The air valves 2 and 41, are such as are commonly used in this art, and have the proper construction so that inflowing gas may pass through the opening 27, Figures 4, for instance, while out-flowing gas and air may pass up through opening 37, through a passage not shown, but commonly provided in such valves to and through the opening 38 to the stack flue 24, and to the stack 25. Valve 26 has also the reversing feature common to such valves, in that opening 37 may be opened to the in-flowing air, while 27 and 38 are then open for the use of the out-flowing air and gas to the stack flue 24, and stack 25. Similar features are part of the other air-valve 41.

These features are very common in the trade and art to which the present invention belongs, and will not be further described herein. A very good and intelligent understanding of the parts of this furnace may be obtained by following the operation of its parts, and such description will now be given.

The gas valve 2, is located at point 3, of Figure 7, and supplies gas from a producer gas generator at a distant point, and same is not shown on the drawings. The gas valve 2 has three openings 4, 5, 6, through which gas may pass to the gas flues 7 or 23. However only one passage is used for in-flowing gas at a time, and the gas flow will be assumed to originate at and pass through the opening 4 preferably for the present descriptive purposes, and thence to flue 7, shown in Figures 1 and 9 of the drawings. Passage 7 communicates with passage 8, and gas regenerator 9, passing up through between the rider-arches or brick 10, and thereby to and through the checker-work brick (not shown) which always are piled upon the rider arches 10. When the furnace is in full operation the gas in chamber 9 is in an ignited condition, so that the checker-brick are in a superheated condition constantly, as is common in regenerative furnaces. As is seen the top of the chamber 9 is arched, and leading therefrom is a vertical conveying gas passage 11, which in its turn leads to a horizontally disposed mixing passage 12, where the gas meets an inflow of air under strong pressure, which is received at point 81 from a source of pressure supply (not shown). The inrushing air diverts the

gas supply inwards toward the furnace chamber 13, and passes over the hearth 14 in a burning condition. Air is supplied to chamber of passage 12 from the air regenerators 31 and 51, through the vertical passages 32, and 69 as will be seen which supplies the needed amount of air for combustion, in the furnace chamber 13, as is at once understood, and will be further described.

On the hearth 14 are placed the glass pots 15, 16, Figure 5. The burning gas and air pass over these pots of molten glass, through the burner port 17, to passage 18, down through passages 19, 65, and 66 to the regenerator chambers 20, 34 and 35. From thence the mixed gas and air in chamber 20 passes along passage 23 to the gas valve opening 6, thence through the opening 5, to stack flue 24, and out of the stack 25. The air flow passes in much the same manner as that just described in reference to the gas-flow. The air valve 26 admits air to the opening 27, thence to, the air passages 28, 29, through the rider arches 30 to the air regenerator 31.

Thence to vertical passage 32 Figure 3, and to passage 12, where it meets the gas from passage 11 just described and is delivered to the furnace chamber 13. The heated gases in the chamber 34 pass through passage 36 to opening 37 in air valve 26, to and through opening 38 to passage 24, and the stack 25. The burned gases from chamber 35 pass through passage 39 to opening 40 of the air-valve 41, through opening 42, to passage 24, and to the stack 25.

It will be noted that while I have described the air flow originating at the air-valve 26; at the same time air is passing through opening 67 of valve 41, and passes through passage 68 to chamber 51, and thence to the vertical passage 69, to passage 12 and mixes with the air from passage 32, and the gas from passage 11 as before described.

It is noted in passing that when the air and gas valves are reversed in the well understood and known manner of all regenerative furnaces, that a contrary flow of gases and air may be obtained through the chambers of all the regenerators described above, and it is believed that this operation is so well known and understood, it is unnecessary to set same out further here.

In many furnaces in common use heretofore, the gas is delivered into a passage which corresponds to passage 11, and its counterpart 19, from a point which is at right angles in direction to these gas passages. It is readily understood that this method of flow soon "burns out" the side wall brick at say points 43, in such furnaces, and the brick falling in said flues block them up, and the furnaces accordingly have to be rebuilt much sooner, than with the present type of furnace, in which the heated gas merely ascends through a vertical flue 11, or 19, and is deflected from

its course in the passage 12, by the strong air pressure acting on it there. This is one of the purposes set out in the preamble to this specification, and tends to prolong the life of the furnace, as some other features set out herein tend to do also, thereby providing a better furnace than those in common use.

Another principal advantage of the present invention, is the proper selected location of the burner ports 33 and 17. The burner port 33 shown clearly in Figure 8 is formed and placed so that the bottom edge 44 of the port is at a higher elevation within the furnace chamber 13 than the tops 45 of the glass pots 15, 16, for the purpose of directing the in-rushing burning gas and air, which is advancing under great pressure into the chamber from the burner port 33, or 17 as the case may be, over the tops of the said glass pots, and not against them, as heretofore commonly done in similar glass furnaces. This results in a great saving of glass pots, as is at once apparent, and this feature is one of the principal advantages of my invention.

The arrangement of the parts of the present invention, result in a clear advantage when cleaning of the air and gas regenerators is required. Due to the entire removal of the usual producer gas generators (not shown) from points 46, 47, between the two banks of regenerators 58 and 59, and the construction of the passageway 52 therebetween, it is seen that "doors" are placed at 48, 49, 50 in the inner ends of the regenerators, in both banks of the same. The arched passage 52 being capacious enables the air cleaning hose used to clean out the checker-work brick in all the regenerator chambers, to be readily used from the inner ends of these chambers. This is a new feature of the present invention, and especial attention is drawn thereto. The doors placed at the outer ends, to wit at 53, 54, 55 of the regenerator chambers, are in common use, but the great advantage of being able to clean out these chambers both from the inner and the outer ends thereof, is a distinct advantage in this art, and it is believed needs no further emphasis herein.

A novel feature of the invention in hand is what I have named the "cleaning stones", as shown in Figures 5 and 9 of the drawings. These cleaning stones are numbered 82, and preferably made in several sections, and of special clay, sloped and curved somewhat in a cupped form, but always inclined towards their outlets 56, 57 etc., and used for carrying away automatically by gravity, the overflow of molten glass and impurities from the glass pots 15 on the furnace hearth 14. This arrangement of cleaning stones, and orifices therefrom, avoids the necessity of using scrapers having very long handles for cleaning the furnace hearth 14, and also eliminates the necessity of opening the side doors of a furnace, in order to accomplish the cleaning

operation. Ordinarily any slag, or débris found at hand at the factory is used to stop up the orifices 56, 57, and this is pushed out of position temporarily, when a poker or other iron rod is pushed in the orifices, to forward the discharge of said impurities from the hearth of the furnace. However it is found, as these impurities are kept constantly in motion, by the shape and form of the cleaning stones leading always to the various orifices at the outer side walls of the furnace, that very little other attention is needed.

Another feature of the present furnace is, that having two separate banks of furnace regenerators of comparatively short length each, from points 60 to 61 for instance, requires longitudinal binding channels of short length, and practically no bulging of the regenerative chamber occurs at points 62, 62. This is readily seen to be true, when attention is called to the fact that many furnaces in common use, have binding channels of a length equal to the over-all length of the present furnace, say from point 63 to 64, with very little chance for transverse binding, due to the producer gas generators being placed at 46, 47, between the two banks of regenerators 58 and 59 heretofore. It is evident that the ability to pass completely around the two banks of regenerators, enables a rigidly built furnace to be constructed, all of which prolongs the life of the individual furnace. In many of the old type furnaces supports intermediate the length of the longitudinal binding channels had to be provided to take care of the bending moment at these points. This is readily evident when the great heat of the regenerator chambers, and the overall length between points 63 and 64 are considered, and the binding channels have to extend continuously between said points.

With reference to the improved temperature and ventilation conditions in the casting hall basement which immediately surrounds the air and gas regenerators, it is seen that the arched passage 52 permits good circulation of air, completely around the two banks of regenerators 58 and 59, and the cooling effect of the air circulating completely around same, produces very desirable and comfortable temperature and ventilation in this basemest, for the workmen operating the furnace. This is a novel and advantageous feature obtained by my invention, due to the convenient and spacious placement of the furnace regenerators, and to the removal of the producer gas generators to a distant point from the furnace, and from their position between said regenerators, as has been the practice in the glass-making industry hitherto.

It is seen in the drawings that ventilation and cooling chambers and flues for cooling the furnace hearth 14, are provided in Fig-

ures 6 and 8. The chamber or flue 70 extends beneath the furnace hearth 14, and as seen in Figure 3 the circulating and cooling air passes up in the openings 71 to the bottom side of the clay bottom 83 of said hearth 70. Air gains admission to chamber 70 through the openings 72, 72 in the roof 73 of the arched passage 52. As seen in Figures 3 and 6, the passage or chamber 70 connects with vertical flues 74, 75 on each end of the furnace 1, and thus cooling air is drawn in at the openings 72, 72, and discharged through flues 74, and 75, and the movement of the air in chamber 70 cools the furnace hearth as is at once understood. The Figure 1 of the drawings shows a stone damper 76 in the stack flue 24, which replaces the metal damper commonly used for this purpose, and it is evident a great deal of advantage is obtained by the use of same, as a stone damper does not warp by exposure to heat, and as a result operates smoothly in its grooves 77, 77, a thing not possible when metal dampers which jam in their runway grooves, due to such warping, are used. 90

Attention is directed to the location of the gas and air valves 2, 26, and 41, and the relative distances between these parts, and their relation in position with respect to the sides of the furnace, as it is evident they are placed comparatively far apart for the purpose of obtaining greater ease in cleaning them, and in operating the furnace.

It will be noted the rider-arches of brick 30, shown in Figures 4 and 8 of the drawings, which support the usual checker-work brick (not shown) and are mounted over the passages 8, etc., beneath each of the gas and air regenerators, are much stronger than the usual plain tile, commonly used for this purpose, and thus the checker-work brick in each of these chambers remain in position longer, and thereby the life of the furnace before rebuilding is greatly extended.

I claim:

1. In a glass furnace, a unitary structure comprising a pair of banks of regenerators positioned with their ends adjacent to each other, forming an arched passageway having a roof between them, a heating furnace having a hearth, superimposed on the two banks of regenerators, the size of which is formed co-extensive with the area covered by the regenerators, and the arched passageway between same; and means for cooling the furnace hearth comprising a series of longitudinal ventilation flues positioned beneath and in close proximity to the said hearth, each flue having a port which opens into the roof of the arched passage.

2. In a glass furnace, a pair of banks of air and gas regenerators, the ends of which are in proximity to each other, a transversely sloped hearth in the furnace, the surface of which is inclined downwardly towards the

walls of the furnace, on each side of its median line, an arched roof joining the ends of the two banks of regenerators, and forming a draft passage therebetween, said roof being provided with a number of ports therein, a plurality of longitudinal ventilating flues beneath the furnace hearth, each of which is in communication with one of the arched roof ports, for cooling the furnace hearth, and a plurality of cupped and transversely inclined cleaning stones formed in, and along both side edges of the furnace hearth, each of which is provided with a focal point of débris discharge near the side walls of the furnace.

15 3. In a glass furnace, a pair of banks of air and gas regenerators the ends of which are in proximity to each other, an arched roof joining the ends of the two banks of regenerators, and forming a draft passage therebetween, a plurality of longitudinally disposed ventilating flues beneath the furnace hearth, each of which is in communication with a port in the arched roof, for creating a cooling draft beneath the hearth of the furnace.

16 4. In a glass furnace hearth, a transverse hearth-bed surface on each side of the median line of said hearth, each surface being inclined downwardly towards the sides of same, a plurality of longitudinal cooling and ventilating flues beneath the hearth-bed, in close proximity therewith, each of said flues having a port in direct communication with outside atmospheric air, and means for providing a draft near the said flue ports for the purpose of frequent renewal of the cooling air within said ventilating flues.

5. In a glass furnace hearth, a transverse hearth-bed surface on each side of the median line of said hearth, each surface being inclined downwardly towards the sides of same; a series of cupped cleaning stones in each hearth-bed surface, in inclined surface alignment with said bed surfaces, and each cleaning stone having a focal point of débris discharge near the side edges of the hearth; and a plurality of longitudinal cooling and ventilating flues beneath, and in proximity with the hearth-bed, each flue having a port in direct communication with atmospheric air, and means for providing a draft near the flue ports for the purpose of frequent renewal of the cooling air within the ventilating flues.

In testimony whereof I affix my signature.
JOSEPH HAULIK.
